United States Patent Office.

MORTON JUDD, OF NEW HAVEN, CONNECTICUT.

Design No. 3,796, dated December 21, 1869.

DESIGN FOR A WARDROBE-HOOK.

The Schedule referred to in these Letters Patent and making part of the same

---

To all whom it may concern :

Be it known that I, MORTON JUDD, of New Haven, in the county of New Haven, and State of Connecticut, have invented a new Design for Wardrobe-Hook; and I do hereby declare the following, when taken in connection with the accompanying drawing, to be a full, clear, and exact description of the same, and which said drawing constitutes part of this specification, and represents a side view.

This invention relates to a design for wardrobe-hooks, being the combination of three hooks upon a single base, that is to say, the lower hook curved from the

base to form a hook, the centre being a straight-headed pin, extending from the base, and the third curved from the rear end upward, and from the base, upon the back or reverse side, a spike is attached for convenience of securing the hook, all as fully shown in the accompanying photographic illustration.

I claim, as my invention—

The design for wardrobe-hook, as shown.

MORTON JUDD.
